(57) **CLAIM**

The ornamental design for a soft chest protector, as shown and described.

DESCRIPTION

FIG. 1 is a perspective view of a soft chest protector.

FIG. 2 is a front view of a soft chest protector.

FIG. 3 is a back view of a soft chest protector.

FIG. 4 is a left side over the shoulder perspective view of a soft chest protector, the right side view being a mirror image thereof; and,

FIG. 5 is a top view of a soft chest protector.

The broken lines depict portions of the soft chest protector that form no part of the claimed design.
